UNITED STATES PATENT OFFICE.

ELBERT E. C. WELTY, OF EASTLAND, TEXAS.

FOLDING CHICKEN-COOP.

1,187,875.

Specification of Letters Patent. Patented June 20, 1916.

Application filed March 27, 1915. Serial No. 17,480.

To all whom it may concern:

Be it known that I, ELBERT E. C. WELTY, a citizen of the United States, residing at Eastland, in the county of Eastland and State of Texas, have invented certain new and useful Improvements in Folding Chicken-Coops; and I do hereby declare the following to be a full, clear, and exact description of the invention, such as will enable others skilled in the art to which it appertains to make and use the same.

The invention relates to improvements in folding chicken coops.

The object of the present invention is to improve the construction of chicken coops and to provide a simple, inexpensive and practical chicken coop of strong and durable construction, capable of being compactly folded for shipping or storing and adapted to be easily and quickly arranged for use.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawings Figure 1 is a plan view of the folding chicken coop constructed in accordance with this invention, and shown arranged for use, Fig. 2 is a side elevation of the same, Fig. 3 is an end elevation of the chicken coop, Fig. 4 is a plan view showing the coop partly folded, Fig. 5 is a side elevation the parts being arranged as shown in Fig. 4, Fig. 6 is a side view showing the parts folded, Fig. 7 is a detail perspective view illustrating the manner of securing the members of the coop together.

Like numerals of reference designate corresponding parts in all the figures of the drawings.

In the accompanying drawing in which is illustrated the preferred embodiment of the invention, the folding chicken coop comprises in its construction a bottom 1, side walls 2, end walls 3 and a top wall 4. The bottom or floor which may be constructed of any suitable material is composed of two sections 5 and 6 connected together by a longitudinally disposed centrally arranged pintle rod 7 passing through registering eyes

8 of the sections 5 and 6 and hinging the same together to permit the said sections to fold compactly as hereafter fully explained.

The central pintle rod 7 is provided with 60 terminal eyes 9 forming heads and adapted to prevent longitudinal movement of the pintle rod with respect to the eyes and also constituting pins for securing the members of the crate in their position for use. The 65 section 5 of the bottom is also provided at its outer edge with eyes 10 in which is arranged a pintle rod 11 constituting the lower side rod of the adjacent side wall of the coop and hinging the bottom to such 70 side wall as clearly illustrated in Fig. 4 of the drawings. The other longitudinal section of the bottom is provided at its outer edge with eyes 12 in which is arranged the outer rod 13 having terminal eyes 14. 75

The side walls 2 which may be of any preferred construction preferably consist of wires or rods extending vertically and horizontally as shown and suitably connected at their points of intersection. The end 80 walls which are also preferably constructed of wire or similar material are composed of two sections 15 hinged together at their adjacent portions by a central vertical pintle rod 16 and also hinged at their outer portions to the side walls by outer corner pintle rods 17. The hinged sections of the end walls are adapted to break or fold inwardly as illustrated in Fig. 4 of the drawings to 85 permit the chicken coop to collapse laterally. The top 4 of the chicken coop is also composed of longitudinally disposed sections 18 hinged together at their adjacent portions by a central longitudinal pintle rod 19. One of the sections 18 of the top of the 90 chicken coop is provided at its outer edge with eyes 20 which are arranged on the top rod or wire of the adjacent side wall of the chicken coop whereby the top is hinged to 95 the said side wall.

The other section of the top of the coop is provided at its outer edge with a rod 21 having terminal eyes 22 and the central pintle rod 19 is also provided with eyes 23. The central pintle rod 16 and the corner 105 rod 17 at the ends of the coop are provided at their lower terminals with eyes 24 and 25 which are adapted to be passed through the eyes 9 and 14 of the central and side rods 7 and 13 of the bottom of the coop and 110 the said eyes are secured together by pins 26 and 27 which pass through the eyes 24

and 25 whereby the sides and end walls are rigidly connected to the bottom and the latter is rigidly held against the lower edges of the said wall. The top of the coop is 5 secured to the side and end walls by pins 28 and 29 passing through eyes 30 and 31 of the central pintle rods 16 and the corner rod 17. The eyes 30 and 31 are passed through the eyes 23 and 22 respectively 10 after which the pins are passed through the said eyes 30 and 31. Any other suitable means may be employed for securing the members of the crate in their operative position to form a rigid coop or crate. 15 When it is desired to fold the chicken coop the pins are withdrawn and the ends are moved inwardly to cause the crate to collapse laterally and the top and bottom of the coop are folded against the exterior 20 of the adjacent side walls to which they are hinged. This enables the chicken coop to be quickly and compactly folded for returning to the shipper or other purpose. The top of the chicken coop is provided with 25 a suitable door 32 which may be of any desired construction and which may also be arranged at any preferred point. Although the improvements are shown applied to a folding coop it will be apparent that they 30 are also applicable to various other forms of shipping crates or packages.

What is claimed is:—

1. A folding receptacle of the class described including side walls, end walls 35 hinged to the side walls and composed of hinged sections collapsible inwardly, a foldable bottom composed of hinged sections and connected to one of the side walls, a foldable top composed of sections and connected to the other side wall, and interfitting eyes carried by the top, bottom, side and end walls and adapted to receive fastening means for securing the parts in position for use.
2. A folding receptacle of the class described including a bottom composed of sections, a pintle rod connecting the sections and provided with eyes, side walls, end walls hinged to the side walls and composed of sections, vertical pintle rods connecting the sections of the end walls and

provided with eyes arranged to extend through the eyes of the pintle rod of the bottom, fastening means for securing the said eyes together, and a foldable top.

55

3. A folding receptacle of the class described including a bottom divided longitudinally into two sections, a pintle rod connecting the two sections and provided with terminal eyes, a side rod carried by one of the sections of the bottom and located at the outer edge thereof, said side rod being provided with terminal eyes, side walls, one of the side walls being hinged to the other section of the bottom at the outer edge 60 thereof, end walls composed of sections, central and corner pintle rods hinging the sections together and to the side walls and provided with eyes arranged to extend through the eyes of the bottom and adapted 65 to receive fastening means, and a top.

60

4. A folding receptacle of the class described including side walls, end walls composed of hinged sections, and having intermediate and corner pintle rods provided 75 with eyes, a top composed of hinged sections and provided with pintle rods having eyes arranged to receive the said eyes, fastening means for securing the said eyes together and a bottom.

80

5. A folding receptacle of the class described including side walls, end walls composed of hinged sections and provided with central and corner pintle rods having eyes at the upper and lower edges of the said 85 walls, a bottom hinged to one of the side walls and composed of sections hinged together and provided at its other side edge and at the hinge with eyes adapted to receive the eyes at the lower edges of the end 90 walls, and a top hinged at one of its side edges to the other side wall and composed of sections hinged together, said top being provided with eyes located at the other edge of the top and at the hinge thereof and 95 receiving the upper eyes of the end walls.

In testimony whereof I affix my signature in presence of two witnesses.

ELBERT E. C. WELTY.
